UNITED STATES PATENT OFFICE.

GUSTAVUS WILLIAM HAAS, OF LOS ANGELES, CALIFORNIA.

PORTABLE DOOR OR SASH LOCK.

SPECIFICATION forming part of Letters Patent No. 565,978, dated August 18, 1896.

Application filed November 14, 1895. Serial No. 568,926. (No model.)

To all whom it may concern:

Be it known that I, GUSTAVUS WILLIAM HAAS, a citizen of the United States, residing at Los Angeles, in the county of Los Angeles and State of California, have invented a new and useful Portable Door or Sash Lock, of which the following is a specification.

My invention relates to that class of door-securers in which two arms or members are pivoted together by one end and have their other ends provided with points arranged to prevent slipping of the ends, the brace being adapted to be placed in the angle between the door and the floor, or a window and its casing, and sprung into position in the manner of a toggle to force the points into the wood to thus form a brace which securely holds the door or window from being opened until the brace is removed.

20 The object of my invention is to produce a device of this class which will fold into very compact shape and will be provided with a locking-bolt which will be at all times chambered within the device, so that such device will avoid any objectionable projections and will be extremely convenient for carrying in the pocket or valise.

25 A further object of my invention is to provide a device of this kind which will be cheap and extremely easy to manufacture, one which will possess the maximum amount of rigidity and strength with a minimum amount of material and weight.

30 My invention comprises the features of construction and combinations of parts which are hereinafter fully set forth and claimed.

The accompanying drawings illustrate my invention.

Figure 1 is a perspective view showing my 40 newly-invented door and sash lock in position locking a door. Fig. 2 is a view of the same applied ready for locking two sashes of a window. Dotted lines show the position of parts when forced into the locked position. Fig. 3 is an elevation of the under or inner side of the lock. Fig. 4 is a longitudinal mid-section. Fig. 5 is an enlarged sectional detail of the joint. Figs. 6, 7, and 8 show the blanks for forming the brace members and 50 the locking-slide.

My newly-invented lock comprises a door or window securer formed of two arms or

members A A', pivoted or hinged together at one end by a pintle or pivot B and provided at their other or free ends with points *a a'* and stop-shoulders *a'' a'''*, arranged to engage with the wood, such members being formed in channel shape or recessed upon one side and adapted to fold together with the recesses opening toward each other. To prevent the 60 two members from being sprung out of their locked position, I provide a sliding bolt or latch C, which is arranged within the recess of one of the members and is secured thereto by suitable means, such as a screw or stud *c*, 65 working in a slot *a'''*, provided in the base or back of one of the channel members.

D indicates the stop which is formed by the ends of the base or bottom walls of the channel members which engage with each other 70 to prevent the brace from bending in more than one direction.

75 Preferably the two arms A and A' are formed of channel-iron and may be made of sheet metal by being forced through a shaper, or may be cast if deemed desirable. However, I prefer to make the device of sheet metal for the reason that by my construction it is very easily manufactured, and sheet metal is not so liable to be broken as is cast 80 metal.

85 As shown in the drawings, the sheet-metal blanks are each provided at one end with pivot-ears, (shown in Figs. 6 and 7,) and these ears project beyond the base or bottom of the channels when the channels are formed. One member, A', is wider than the other member, A, and the ears of the member A are arranged to chamber between the ears of the member A'. By this construction the member A is adapted to fold inside of the member A', and greater compactness is secured than is otherwise possible. Their position when folded is indicated in dotted lines in Fig. 4. The sliding bolt or latch C is also preferably 95 made of channel-iron, and it and its securing-screw *c* are arranged to slide freely in the member A, so that when the lock is seated in position, as shown in Fig. 1 and in dotted lines in Fig. 2, the latch will drop into place, 100 as in Fig. 4, and extend across the joint far enough to prevent the joint from bending.

The points *a'* of the lower arm A' are preferably made longer than the points *a* of the

upper arm A, so that when the device is applied to the door the points a' will extend through the carpet and seat in the floor. The upper points a are to be made as small as consistent with safety, in order to avoid marring the door or window-sash.

Dotted lines in Figs. 6, 7, and 8 indicate the lines at which the sheet-metal blanks would be bent in order to form the finished arms of the members which form the lock.

To apply the lock to a window, the lower points a' will be set upon the top of the lower window-sash and the upper points a will be seated against the inside of the upper sash, the joint being bent at a suitable angle, substantially as shown in Fig. 2. Then pressure is applied to the joint to press it in toward the sash, thus forcing the points a a' into the upper and lower sash until the brace is in its fully-extended position, as indicated in dotted lines in Fig. 2. As soon as the brace is in its fully-extended position, (shown in Figs. 1 and 4,) the latch C will drop into place by force of gravity and thus prevent the lock from again being opened until the latch is first lifted.

To apply the lock to a door, the lower points a' are seated in the floor, the upper points a against the door, the brace being bent at a suitable angle. Then pressure can be applied by hand or foot until the brace is fully extended, thus forcing the points into the door and into the floor. The greater the angle at which the brace is bent when the points are applied to the door and floor the greater will be the depth to which the points are inserted. Care must be had that the brace is not bent so much as to cause the shoulders a'' a''' to come into contact with the door and the floor before the brace is fully extended, as this would prevent the lock from being effective. It is not necessary that the points fully insert so as to bring the shoulders against the door and floor, for the movement of the door in the act of opening will not be very great before the shoulders will engage the door and floor and thus stop any further movement of the door. The same is true in the case of sliding doors or sash.

The back-stops D of the two arms of the brace are beveled and arranged to allow the members to throw back beyond a right line, so that when the brace is in its fully-extended position any strain brought against the brace by attempting to open the door or window will be carried by all the parts of the joint, and the act of opening or bending the joint to release the door or window will force the free ends of the arms farther apart than when the brace is in its full locking position, so that the resiliency of the material of the door and floor or of the window-sashes, or other parts into which the points are inserted, tends to hold the brace against being bent to release the door or window.

E indicates a rivet-sleeve to hold the rivet-bearings from collapsing.

To manufacture the lock from sheet metal,

the blanks shown in Figs. 6, 7, and 8 are first cut out by dies and then shaped as indicated by the dotted lines. Then the parts are assembled and the joint riveted together by the pintle B. The latch C is then secured in place by the screw c, inserted through the slot a''' and screwed into the latch-piece C. The points are preferably beveled at their inner faces, as shown in Fig. 3, so as not to mar the wood, but to make a neat and practicable imperceptible imprint.

In the drawings I have shown at the end of each arm two points, the angles of which are acute; but it is to be understood that each arm may have but one point and that the points may be rectangular or of any desired angle or may be rounded, if desired, the purpose being to give a sufficient hold in the wood to retain the brace in position when extended. The shoulders absolutely prevent the arms from being inserted so deep into the wood as to allow the door or window to be opened.

Now, having described my invention, what I claim as new, and desire to secure by Letters Patent, is—

1. The door or window securer set forth comprising the two members pivoted together at one end and provided at their other ends with the points and the stop-shoulders, such members being opened or recessed upon one side and adapted to fold together with the recesses opening toward each other; and a bolt arranged within the recess of one of the members, secured thereto and adapted to extend across the joint between the two members when such members are open and to lock them in such open position.

2. The door or window securer set forth comprising the two sheet-metal members bent into channel shape and pivoted together at one end by means of their side walls, and having their other ends provided with the points and the stop-shoulders, one of such members being provided in the base of its channel with a slot; a bolt arranged to slide within the channel of the members, and a stud provided with a head, passed through the slot in the slotted member, fixed to the bolt and adapted to operate the bolt to cause it to extend across the joint between the two members when the members are in their open position.

3. The door or window securer set forth comprising the sheet-metal members bent into channel shape, one of such members being wider than the other member and each member having its side walls provided at one end with pivot-ears projecting beyond the base or bottom of the members, the ears of the narrow member being arranged to chamber between the ears of the wider member, each of said members being provided at its free end with the points and the stop-shoulder, and one of said members being provided in its base or back with a slot; a pivot passing through the ears and arranged to pivot the two ears together; the bolt arranged inside the channel

of one of the slotted members; and the stud passed through the slot, rigidly secured to the bolt, and arranged to operate the bolt to cause it to extend across the joint between the two members when the members are in their open position.

4. The door-securer set forth comprising the two sheet-metal members bent into channel shape, one of such members being wider than the other of said members, and both members having their side walls provided at one end with pivot-ears projecting beyond the base or bottom of the members, the ears of the narrow member being arranged to fit within the ears of the wider member, each member being provided at its free end with the points

and the stop-shoulder, and one of such members being provided in its base with a slot; the rivet-sleeve arranged between the ears; the pivot or pintle passed through the ears and 20 through the rivet-sleeve; the bolt arranged to slide within the channel of the slotted member; and the stud passing through the slot, secured to the bolt and arranged to operate the bolt to cause it to extend across the joint 25 between the two members when the two members are in their open position.

GUSTAVUS WILLIAM HAAS.
